UNITED STATES PATENT OFFICE.

BERTHA SCHARPEN, OF FESSENDEN, NORTH DAKOTA.

DESIGN FOR A HAT.

Application filed October 29, 1923. Serial No. 7,618. Term of patent 7 years.

To all whom it may concern:

Be it known that I, BERTHA SCHARPEN, a citizen of the United States of America, residing at Fessenden, in the county of Wells and State of North Dakota, have invented a new, original, and ornamental Design for a Hat, of which the following is a specification, reference being had to the accompanying drawing, forming a part hereof.

In the drawing:

Fig. 2 is a plan view of the same.

A portion only of the decoration is shown in full lines.

I claim:

The ornamental design for a hat, as shown.

BERTHA SCHARPEN. [L.S.]
